Application September 18, 1936, Serial No. 101,458
In Germany December 19, 1931

15 Claims. (Cl. 235—6)

The invention relates to cash registers, accounting and the like machines having at least one row of interspersed totalizers cooperating with a common differential mechanism, of which 5 totalizers preferably one is a multiple item totalizer, and another a grand totalizer, and more particularly to the selection and the engagement of several totalizers, including the multiple item totalizer and the grand totalizer, during the same 10 amount entering machine operation.

Thus the main object of the invention is to enable simultaneous engagement of several totalizers of the same row during a machine operation.

15 Another object of the invention is to adapt the differential mechanism for such simultaneous engagement of several totalizers.

Still another object of the invention is to adapt the totalizer selection and engagement control 20 means for such simultaneous engagement of several totalizers during amount entering.

Another object of the invention is to provide 25 totalizer selecting means which enable optional selection of one or several totalizers of a row at a time for and during a machine operation.

Another object of the invention is to provide for tens carrying in a machine operation with one or several totalizers of a row engaged.

Another object of the invention is to adapt a 30 tens carrying device to cooperate as well with one as with several totalizers of a row engaged.

Further objects of the invention will be pointed out in the following detailed description with reference to the annexed drawings.

35 A preferred form of an embodiment of the invention is shown in the annexed drawings.

Of said drawings:

Fig. 1 is a side view of a totalizer row with one totalizer engaged and another one not engaged.

40 Fig. 1a is a view of a portion of Fig. 1 to a larger scale.

Fig. 2 is a section along line II—II of Fig. 1.

Fig. 3 is a front view of the totalizer selecting device.

45 Fig. 4 is a transverse section through the selecting device.

Fig. 5 is a side view of the motor key bank.

Fig. 6 is a side view of the multiple-item key bank.

50 Figs. 7, 8, and 9 show the selecting and engaging means in different positions.

Fig. 10 is a side view of the motor key bank with the mode of operation control means.

55 Fig. 11 is a section along line XI—XI of Fig. 10.

Fig. 12 is a side view of the tens carrying device ready for carrying.

Fig. 13 shows the same device after tens carrying is performed.

Fig. 14 shows a portion of the tens carrying 5 device after being restored.

The illustrative machine is equipped with the invented device and has two totalizers, viz: a grand totalizer accumulating all amounts entered into the machine and a sub-totalizer, or multiple-item accumulator, which, upon depression of a multiple-item key, can optionally be brought into engagement for accumulating any series of items of a multiple-item transaction. Heretofore, such totalizers were mounted on different shafts due 10 to the fact that, in case of necessity, they had to be operated commonly, but according to the present invention, they are located in one and the same totalizer row, the adding wheels thereof being mounted one close to another by denominational orders. 15

The amount differentials 10, of each denominational order, are moved during each operation of the machine, first in counter-clockwise direction and then in clockwise direction a distance 25

depending on the amount being entered. Each differential 10 is permanently engaged with a gear 11 (Fig. 1). Each gear 11 is rigidly connected to a gear 11' of same diameter by means of a hub (Fig. 2). At each side of each pair of gears 30 11, 11', there are provided angular levers 12, 12' pivotally mounted on shaft 13. The levers are fast on hubs supported on shaft 13, said hubs extending into the hub of the pairs of gears 11, 11'. 35

The levers are normally held in a set position by a mechanism to be described hereinafter. Intermediate wheels 15, 15' are supported by pins 40 14, 14' of the angular levers 12, 12' respectively (Figs. 1 and 2). The intermediate wheels 15, 15' are constantly in mesh with gears 11, 11' respectively, so that the movements of the differential member 10 of any denominational order are uniformly transmitted to the appropriate intermediate wheels 15, 15'. Further, the intermediate wheels 15, 15', with the differential members 10, 45 and 11, 11' remaining stationary, are capable of performing a movement the same as planetary wheels, the said movement being transmitted to shafts 14, 14' by means of tens carrying levers and intermediate levers 12, 12' as will be described later on. If tens carrying is done directly on the adding wheels, instead of through the 50 wheels 15, 15', the sets of wheels 15, 15' may be omitted and a roll extending through the width of the adding wheels may be provided. This roll 55

is an expedient means for use between overflow wheels of the totalizers. Adding wheels 16 and 16' of the grand totalizer and the multiple-item totalizer, respectively, are mounted opposite the 5 intermediate wheels 15 and 15', each adding wheel 16 facing an intermediate wheel 15 and each wheel 16' a wheel 15'. The adding wheels 16, 16' are pivotally carried by studs 17 and 17' of rock levers 18 and 18' respectively. All the rock levers 18, 10 18' are alternately mounted on a common shaft 20. The said levers are pivotally mounted on shaft 20 (Figs. 1, 3) and are retained against lateral shifting movement thereon. The levers are normally held, in a manner described hereinafter 15 in detail, so positioned that the adding wheels 16, 16' are out of mesh with the intermediate wheels 15, 15'.

Shaft 21 slidably mounted in the side frames of the machine has fastened thereto coupling arms 20 22 (Figs. 1, 3) in number one more than denominational orders are provided. Interspersed with these coupling arms 22, there is provided, loosely mounted on shaft 21, a series of locking levers 23, no space being left between the said levers and 25 the arms. The levers 23 have downwardly extending arms straddling a stationary shaft 24. The locking levers are, accordingly, shifted together with the shaft 21 and locking arms 22, but are locked by shaft 24 against rotation about 30 shaft 21. The other arms of the locking levers 23 lie, with the machine in rest, flush in the same plane as the coupling arms 22, so that the forked ends of the coupling and locking arms 22, 23 form an uninterrupted straight guiding groove. 35 The latter is engaged by the rounded off ends of the arms of the rock levers 18, 18' whereby the adding wheels 16, 16' are prevented from meshing with the intermediate wheels 15, 15'. The shaft 20 carries locking pawls 96, 96', each thereof 40 located aside of one of the rock levers 18, 18', the said locking pawls having noses entering the opposed gaps between the teeth of the adding wheels 16, 16' to lock the said wheels. Upon rocking the rock levers 18, 18' in counter-clockwise direction, 45 in a manner described hereinafter in detail, a stop bar 98 carried by the framework of the machine prevents the locking pawls 96, 96' from taking part in this rocking movement so that their locking noses release the adding wheels 16, 16' after they have been engaged with the intermediate wheels 15, 15'.

The shaft 21 carries a sleeve 28 unshiftably mounted between two spacing collars (Figs. 3 and 4), the said sleeve having secured thereto 55 an arm 29 with a forked end straddling across shaft 30, whereby said sleeve is prevented from rotation. The sleeve 28 has fastened thereto a roller 31 traveling in the circumferential cam groove 32a of a drum 32 which is pivotally but 60 unshiftably mounted on shaft 30. The said drum has fixed thereto a bevel gear 33 meshing with a rotating bevel gear 34 on a pivot 36 fast to shaft 30. The rotating bevel gear 34 meshes also with a bevel gear 35 loosely mounted on shaft 30 65 and rigidly connected to a gear sector 37. The latter meshes with the internal gear of a gear element 38 fast to shaft 39 (Figs. 4 and 5). The shaft 39 carries also an arm 41a connected by means of a link 40 to a moving slide 41 pivoted 70 on the motor key bank. The motor key bank comprises three keys 42, 43, 44 for "Adding", "Read" and "Reset", the said keys having pins 75 cooperating with slide 41 in such a manner that the latter is not moved when the "Add" key is depressed, but shifted downward to an equal

extent when either total-taking key 43, 44 is depressed and the bevel gear 35 is rotated by the gear sector 37, both of said elements being moved through equal angles in both cases. If at this time the bevel gear 34 is prevented from rotating about shaft 30, the drum 32 is rotated through an angle of the same degree as gear 35. Further, the shaft 30 carries a gear sector 46 meshing with the gear sector 47 loosely mounted on shaft 39 (Figs. 4 and 6). Sector 47 is connected by means of a link 48 to a slide 49 associated with the key bank comprising the multiple-item key 50 serving as a means for engaging the multiple-item totalizer. The pin of the multiple-item key cooperates with an inclined surface of the slide 49 in 15 such a manner that the latter is moved downward upon depressing the multiple-item key, at which time the sector 47 is rocked in counter-clockwise direction. The sector 46 transmits this motion of the sector 47 to the shaft 39 whereby 20 the bevel wheel 34 is given a rotating movement through a certain angle. With the bevel wheel 35 remaining stationary this rotating motion causes the drum 32 to rotate in the same direction of rotation but through an angle twice as 25 great as that of bevel wheel 34. Depression of either total-taking motor key 43 or 44, as well as the multiple-item key 50, through gears 33, 34, and 35, rotates the drum 32 three steps.

The cam groove 32a is so shaped that, with the machine in rest, that is, if either total key 43, 44 or the multiple-item key 50 have not been depressed, the coupling arms 22 fast on shaft 21 embrace the rock levers 18 carrying the adding wheels 16 of the grand totalizer, while the rock 35 levers 18', carrying the adding wheels 16' of the multiple-item totalizer, are held by the stationary locking arms 23 as shown in Fig. 3.

The shaft 21 carries an arm 54 (Fig. 10) rigidly mounted thereon, but in such a way it is not 40 compelled to take part in the lateral movements of the shaft 21, the said arm 54 being connected to one arm of a coupling lever 57. The coupling lever 57 is pivoted on the middle shaft 58 of the machine and carries three coupling pawls 60, 61, 45 62, each one thereof being connected by means of a slot and pin connection to a motor key 43, 42, 44 in such a way that upon depressing the respective motor key, the respective pawl is rocked inwardly. A stud 63 of the motor key bank 50 (Figs. 10, 11) supports a mode of operation cam disk 67 with a cam groove 67a, and a stud 64 supports a twin mode of operation cam disk 65, 66 55 with a cam groove 65a on the right-hand side, and a cam groove 66a on the left hand side. Each mode of operation control cam disk 65, 66, 57 is provided with teeth to mesh with a gear 68 whereby the said disk is given a full revolution during a machine operation. The cam grooves 65a, 66a, 67a of these disks are each engaged by a roller 60 70a of a pitman 70. The pitmans are bifurcated at one end to straddle and be guided by the respective studs 63, 64, and have their other ends linked to the arms of the related angular levers 71, 72, 73. The latter are pivoted on studs 74 65 of the motor key bank and are provided with pins 71a, 72a, and 73a respectively, normally opposite the recesses of the appropriate coupling pawls 60, 61, 62 respectively. The cam grooves 65a, 66a, 67a are so shaped that upon rotation 70 of the cam groove disks, said grooves cause their respective angular levers 71, 72, 73 to rock first in clockwise direction and then in counter-clockwise direction. The cam grooves of the individual disks 65, 66, 67, however, are arranged relatively 75

to one another, so that rocking the angular levers is timed in accordance with the operations of the machine.

By depressing any motor key 42, 43, 44 the respective pawl 60, 61, or 62 is engaged with the pin 71a, 72a, 73a of the respective angular lever 71, 72, or 73 respectively, whereby the coupling lever 57 is coupled with the respective mode of operation disk 65, 66, or 67 and is rocked first in clockwise and then in counter-clockwise direction upon operation of the machine at the times determined thereby.

The rocking movement of the coupling lever 57 is transmitted to the coupling shaft 21 by means of the pulling rod 55 and the arm 54 whereby the coupling arms 22 of the said shaft swing the rock arms 18, 18', engaged with said arms at the time, in such a way that the selected adding wheels 16, 16' are moved into engagement with the intermediate wheels 15, 15'. According to whether the coupling arms 22 embrace the one only, or both the groups of rock arms 18, 18', the one totalizer only, or both totalizers are coupled with the intermediate wheels 15, 15' and with the differential members 10 respectively.

As the two totalizers of this row contain different totals, it may occur, when both the totalizers are operated simultaneously, that in some denominational orders the adding wheel of the one totalizer passes from "9" to "0", while the adding wheel of the other totalizer does not do so. For this reason, two tens transfer mechanisms, operating simultaneously, are provided, as will now be described.

Each adding wheel 16 of the grand totalizer has closely arranged thereto a disk with a tens carrying tooth 75 (Figs. 1 and 2) capable of cooperating with tooth 76 of a tens carrying pinion 77 when the adding wheel passes from "9" to "0". The tens carrying pinion 77 is pivoted on a stationary shaft 78 and is provided with a laterally extending pin 79 engaging a recess 81 of a rock lever 82. The bail shaped rock lever 82 is mounted on shaft 80 and its other arm 84 carries a pin 85 engaging the forked end of the angular lever 12 of the next higher denominational order. The opening 81, cooperating with the shaft 78 and the pin 79 of the tens carrying pinion, is so shaped that the lever 82 cannot be rocked with the pinion 77 in rest position shown in Figs. 1 and 1a. Thereby also the angular lever 12 carrying the intermediate wheel 15 of the next higher denominational order, is held in its rest position. Now if, while an amount is entered, an adding wheel 16 of the engaged totalizer passes from "9" to "0", the tens carrying tooth 75 rotates the tens carrying pinion 77 in counter-clockwise direction (Fig. 12) by 45 degrees, during which rotation the pin 79 is sweeping along a surface, concentric with shaft 78, of the opening 81 without rocking out the lever 82. At this time the tooth 92 of the tens carrying pinion comes into the path of the teeth 88, 89 of a stepped disk 87 secured to a shaft 86 which is oscillatorily driven. After the tens carrying has been prepared, the shaft 86 is given a part rotation in clockwise direction, at which time the two teeth 88, 89 of the stepped disk 87, secured to this shaft, rotate the pinion 77 in counter-clockwise direction by 90 degrees. At this time the pin 79 rocks the lever 82 in clockwise direction, the latter rocking, in its turn, the angular lever 12 in counter-clockwise direction whereby the intermediate wheel 15 like a planetary wheel rolls down the gear 11, which is held stationary at this time, and advances by one unit

the adding wheel 16 of next higher denominational order (Fig. 13). Thereupon the locking disk 94 passes beneath the wide tooth 95 of the tens carrying pinion locking it against rotation in clockwise direction. After the tens carrying has been completed, the totalizer becomes disengaged and the shaft 86 is turned back in counter-clockwise direction beyond its initial position (Fig. 14). At this time the teeth 88, 89 of the stepped disk 87 turn back the tens carrying pinion 77 by 90 degrees, and the tooth 90 of a reversing disk 91 causes a further back rotation by 45 degrees, so that the tens carrying pinion 77 regains its initial position. At this time the pin 79 rocks the lever 82 back, whereby also the planetary wheel carrier 12 with the planetary wheel 15 is restored. Thereupon the shaft 86 is turned back in clockwise direction to initial position, so that the parts are positioned as shown in Fig. 1, however, both totalizers being disengaged.

The other totalizer 16' of this row is provided with like tens carrying elements referred to by the same reference numerals with prime marks (') added thereto. In order to effect tens carrying from any denominational order of the one totalizer to the next higher order of the same totalizer, in spite of the fact that an order of the other totalizer is lying in between two denominational orders of the other totalizers, the bails 83 and 83' of the rock levers 82 and 82' are alternated, so that none thereof hampers the movement of the other lever (Figs. 1 and 2).

The operation of the device described is as follows:—

(1) During an adding operation of the machine for entering a single item, the adding motor key 42 is depressed, but not the multiple-item key 50. Due thereto, the cam groove drum 32 is not rotated and, in connection therewith, the coupling shaft 21 is not shifted laterally from its rest position (Fig. 3). At this time the coupling arms 22 engage the rock arms 18 carrying the adding wheels 16 of the grand totalizer, while the rock arms 18' of the multiple-item totalizer 16' remain connected to the locking arms 23, and the locking pawls 96, 96' hold the adding wheels 16, 16' against unintentional rotation. Upon depression of the adding motor key 42, by engaging the coupling pawl 60 (Fig. 10) the coupling lever 57 is connected with the cam groove disk 65 for "adding" which, now, rocks clockwise the shaft 21 before the amount differential elements 10 are restored, and thereby rocks the swing levers 18 embraced by the coupling arms 22, so that the adding wheels 16 of the grand totalizer are engaged with the pertinent intermediate wheels 15 during the restoration of the amount differential means 10 (Fig. 1). If, during the entry of an amount, some adding wheels 16 pass from "9" to "0", the tens carrying pinion 77 is rocked 45 degrees in counter-clockwise direction (Fig. 12). Thereby the first tooth 92 of the tens carrying pinion comes into the path of the teeth 88, 89 of the stepped disk 87, so that upon the subsequent clockwise rotation of shaft 86, the pinion 77 is rotated further in counter-clockwise direction by 90 degrees by means of these teeth (Fig. 13). When this occurs, the lateral extending pin 79 of the pinion 77 rocks the bail-shaped lever 82 in clockwise direction and thereby the planetary wheel carrier 12 of next higher denominational order in counter-clockwise direction. During this movement, the intermediate wheel 15, acting as a planetary wheel, rolls down the gear 11, the latter being stationary at this time, and

causes thereby the respective adding wheel 16 to be advanced by one unit. The rotation of the shaft 21 by the cam groove 65a (Figs. 10, 11) causes the grand totalizer to be disengaged. It is not necessary to restore shaft 21 since it was not moved out of its normal position during this machine operation. After the tens carrying elements have been restored to normal positions when the teeth 88, 89, and 90 become operative while the shaft 86 is turned back by the disks 87 and 91 (Fig. 14), all the parts are again in normal positions.

(2) For entering an amount of a multiple-item transaction, the grand totalizer as well as the multiple-item totalizer 16' has to be operated and, therefore, the multiple-item key 50 and the adding key 42 are depressed. By depressing the multiple-item key 50 the cam groove drum 32 (Fig. 3) is turned two steps and the shaft 21 is moved accordingly two steps to the left, which causes the coupling arms 22 to embrace the swing arms 18, 18' of both totalizers (Fig. 8). Depressing the adding motor key 42 causes the coupling lever 57 to be connected with the mode of operation disk 65, so that the adding wheels 16, 16' of the two selected totalizers are disengaged from the intermediate wheels 15, 15' during the restoration of the amount differential elements 10. If, during entry of an amount one adding wheel 16, 16' of each totalizer passes from "9" to "0", each of the tens carrying actions prepared thereby is transferred to the adding wheels 16, 16' of next higher denominational order of the respective totalizer by means of either tens carrying mechanism operating separately from the other. After the two totalizers have again been disengaged by shaft 21, the said shaft and the tens carrying elements are restored to normal.

(3) To take a sub-total, or total from the grand totalizer 16, only the respective total taking key 43 or 44 has to be depressed, whereby the shaft 21 is shifted by one unit to the left, in which position its coupling arms 22 embrace the rock levers 18 (Fig. 7). Upon depression of either total-taking key 43 or 44, the coupling lever 57 is coupled with the respective mode of operation cam disk 66 or 67 (Fig. 10), so that the shaft 21 with its coupling arms 22 is rocked out before the differential elements 10 are set, and the adding wheels 16 of the grand totalizer are brought into mesh with the intermediate wheels 15 (Fig. 1). The adding wheels 16 are rotated in a direction reverse to the additive direction by the differentials 10 until the tens teeth 75, engaging the tens teeth 76 of the pinions 77, arrest the adding wheels 16 in their zero positions. In connection therewith, the grand totalizer is disengaged after the differential elements have either been set or restored to normal positions according to whether key 43 or key 44 has been depressed.

(4) To reset the multiple-item totalizer 16', the motor key 44, and in addition, the multiple-item key 50 have to be depressed, whereby the cam groove 32 is caused to rotate and, in connection therewith, the coupling shaft 21 is shifted three steps (Fig. 9). At this time the coupling arms 22 engage only the rock arms 18' effecting, when the shaft 21 is rotated, the engagement between the adding wheels 16' of the multiple-item totalizer and the intermediate wheels 15' and the differential elements 10 respectively. As, upon depressing the motor key 44, the lever 57 is connected with the mode of operation disk 67, the

multiple-item totalizer, after being reset, is disengaged by the shaft 21 when being turned back.

While the form of mechanism herein shown and described is admirably adapted to fulfill the object primarily stated, it is to be understood that it is not intended to confine the invention to the one form or embodiment herein disclosed, for it is susceptible of embodiment in various forms, all coming within the scope of the claims which follow:—

What is claimed is:

1. In a machine of the class described, the combination of a plurality of interspersed totalizers, a single set of actuators for the totalizers non-shiftable in a lateral direction, a pivoted member to carry each digit wheel of the totalizers, said pivoted members being movable about their pivots only, the digit wheels being non-shiftable in a lateral direction in relation to the actuators, and means to rock the members about their pivot points to connect all of the interspersed totalizers with the actuators for an adding operation of the machine.

2. In a machine of the class described, the combination of a plurality of interspersed totalizers, a single set of actuators for the totalizers, a pivoted member to carry each digit wheel of the totalizers, means coacting with the pivoted members to move the pivoted members about their pivot points, and means to laterally shift said means to select the pivoted members of one or more of the totalizers, whereby one or more of the totalizers are connected with the single set of actuators for an adding operation of the machine.

3. In a machine of the class described, the combination of a multiple item totalizer and a grand totalizer interspersedly arranged in a single row; actuating mechanism constructed for simultaneous cooperation with both totalizers; means for shiftably mounting the totalizers for simultaneous or individual engagement with the actuating mechanism; and variably shiftable means selectively cooperable with the totalizer mountings to determine which of the totalizers shall engage the actuating mechanism.

4. In a machine of the class described, the combination of a row of interspersed totalizers; differential mechanism constructed for simultaneous cooperation with every one of said totalizers; means for mounting said totalizers for individual movement to engage the differential mechanism; means selectively engageable with one or more of said totalizer mountings; means to adjust the selectively engageable means to cause its selective engagement with one or more of said totalizer mountings; and means to operate the selectively engageable means to cause it to move the totalizer or totalizers whose mountings are engaged by the selective means, into engagement with the differential means.

5. In a machine operable to perform a plurality of types of machine operations, the combination of a row of interspersed totalizers; differential mechanism constructed for simultaneous cooperation with said totalizers; means for mounting the totalizers for individual engagement with the differential mechanism; means selectively cooperable with the totalizer mountings for selecting one or more of the totalizers for engagement with the differential mechanism; means to adjust the selective means so that it cooperates with the mountings for one or more of the totalizers; a first means to operate the adjusting means in a certain type of operation

to cause the selective means to cooperate with the mountings for a plurality of the totalizers; and a second means to operate the adjusting means in certain other types of operation to cause the selective means to cooperate with the mounting of only one of said totalizers.

6. In a machine adapted to perform a plurality of types of operations, the combination of a row of interspersed totalizers; differential mechanism 10 cooperable with said totalizers; means for supporting said totalizers for individual movement to engage the differential mechanism; laterally shiftable means selectively cooperable with the totalizer supporting means to select the totalizers 15 for engagement with the differential mechanism; a plurality of manipulative control devices; and means operated by one of said manipulative control devices to shift the laterally shiftable means to select a plurality of the totalizers for engagement 20 with the differential mechanism in one type of operation and said means also being operated by other of said manipulative devices to select one of the totalizers for engagement with the differential mechanism in other types of operations.

7. In a machine of the class described, the combination of a row of interspersed totalizers including a multiple item totalizer and a grand totalizer; actuating mechanism constructed for 30 simultaneous engagement by said totalizers; means so supporting the totalizers as to enable them to be separately moved into engagement with the actuating mechanism; adjustable means simultaneously cooperable with the supporting 35 means for the multiple item totalizer and the grand totalizer to select these totalizers for engagement with the actuating mechanism; means to adjust the adjustable means so that it selects both totalizers; and means to operate the adjusted 40 means to simultaneously move the selected totalizers into engagement with the actuating mechanism during a multiple item entering operation.

8. In a machine of the class described, the combination of a multiple item totalizer and a grand totalizer interspersedly arranged in a single row; differential mechanism formed for simultaneous cooperation with both of said totalizers; means for supporting the totalizers for individual movement toward said differential mechanism; means 50 shiftable to a plurality of positions to selectively cooperate with one or both of said totalizer supporting means; a multiple item key; means operated by the key to shift the shiftable means 55 to a position in which it cooperates with both totalizer supports; and means to thereafter operate the shiftable means to move both totalizers simultaneously into engagement with the differential mechanism.

60 9. In a machine of the class specified, the combination of a row of interspersed totalizers including a multiple item totalizer and a grand totalizer; differential mechanism formed for simultaneous cooperation with said totalizers; means for supporting said totalizers for individual engagement with the differential mechanism; a shiftable means selectively cooperable with the supporting means for either or both of said totalizers; a first manipulative device; a second manipulative device; and means operated by either or 65 both of said devices to variously shift the shiftable means so that it cooperates with both totalizer supporting means when the first manipulative device is operated alone and cooperates with the 70 grand totalizer supporting means when the sec-

ond device is operated alone and cooperates with the multiple item totalizer support alone when both of the manipulative devices are operated together.

10. In a machine of the class described, the combination of a row of interspersed totalizers including a multiple item totalizer and a grand totalizer; differential mechanism including a toothed setting member for each order of the totalizers, means driven by said setting member and associated with each of the totalizers, and a plurality of pinions meshing with said driven means; means for mounting the totalizers to enable the totalizers to be separately shifted into engagement with the pinions; means selectively engageable with the mounting means for each of said totalizers; means for adjusting the selective means to engage either or both of the means for mounting said totalizers to select the totalizers for engagement with the pinions; and means for operating the selective means, after it has been adjusted, to shift the selected totalizers into engagement with the pinions.

11. In a machine of the class described, the combination of a plurality of interspersed totalizers; a plurality of pivoted members, one to carry each digit wheel of the totalizers; a single support upon which the members are pivoted; a single set of actuators common to said totalizers; means selectively engageable with the pivoted members; means to engage the last-mentioned means with the pivoted members for one or more of the totalizers; and means to operate the said last-mentioned means, after it has engaged the members, to rock the engaged members to move 35 the digit wheels carried by the members into engagement with the actuators.

12. In a machine of the class described, the combination of a plurality of interspersed totalizers; a plurality of pivoted members, one to 40 carry each digit wheel of the totalizers; a single support upon which the members are pivoted; a projection on each of the members; a single set of actuators for said totalizers; means shiftable to a plurality of positions to selectively engage the projections on the members for one or more of the totalizers; means to shift the last-mentioned means to a position to engage the projections for more than one of the totalizers; and means to operate the shiftable means to cause the members 50 whose projections are engaged by the shiftable means, to pivot about their support and carry the digit wheels into engagement with the set of actuators.

13. In a machine of the class described, the combination of a row of interspersed totalizers; differential mechanism formed for simultaneous engagement by the totalizers of said row; totalizer supporting means individual to each totalizer to enable the totalizers to be shifted individually to 60 engage the differential mechanism; means shiftable different extents and selectively cooperable with the supporting means for the totalizers to select one or more of the totalizers for engagement with the differential mechanism; a plurality 65 of manipulative control devices; shifting means for said shiftable means operated different extents by certain of said devices when they are operated alone and also operable another extent by a joint operation of said devices; and means for operating 70 the shiftable means, after it has been shifted by the devices, to move the selected totalizers into engagement with the differential mechanism.

14. In a machine operable to perform amount entering and total taking machine operations, the 75

combination of a multiple item totalizer and a grand totalizer interspersedly arranged in a single row; differential mechanism including a plurality of toothed setting members, one common to each 5 order of the totalizers, toothed wheels equal in number to the number of totalizers driven by each settable member, and pinions meshing with said toothed wheels; means for individually supporting the totalizers for separate movement into 10 engagement with the pinions; laterally shiftable means to selectively engage one or both of the totalizer supporting means to select the totalizers for engagement with the pinions; means to shift the laterally shiftable means to cause it to selectively engage both of the totalizer supporting 15 means in certain amount entering operations and either of the totalizer supporting means in certain total taking operations; and means to rock the laterally shiftable engaging means to thereby 20 move the selected totalizer or totalizers into engagement with the pinions.

15. In a machine of the class described, the combination of a row of interspersed totalizers including a multiple item totalizer and a 25 grand totalizer; differential mechanism including toothed setting members associated with the totalizers of said row, toothed wheels driven by said setting members, and pinions meshing with

the toothed wheels; individual means for mounting said multiple item totalizer and said grand totalizer for separate engagement with the pinions; a member settable to three positions and having means thereon selectively engageable with 5 the totalizer mountings so that in one position of the member the means thereon will engage the mounting for the multiple item totalizer, in another position the means thereon will engage the mounting for the grand totalizer, and in 10 another position the means thereon will engage both totalizer mountings; an add key; a total key; a multiple item key; means operated by the multiple item key to move the member so that the means thereon engages both mountings and operated by the total key to move the member so that the means thereon engages the mounting for the grand totalizer and operated by the joint operation of the multiple item key and the total key to move the member so that the means thereon engages the mounting for the multiple item totalizer; and means for rocking the member to move the totalizers, whose mountings are engaged by the means on the member, into engagement with the pinions.
